By Louis Nauclerc Attorney

UNITED STATES PATENT OFFICE.

EMILE VICTOR PREUSS, OF TXELLE, NEAR BRUSSELS, BELGIUM.

APPARATUS FOR THE FABRICATION OF CONCRETE-CONSTRUCTION ELEMENTS.

Application filed July 11, 1922. Serial No. 574,241.

To all whom it may concern:

Be it known that I, EMILE VICTOR PREUSS, a subject of the King of Belgium, residing at Txelle, near Brussels, Belgium, have invented certain new and useful Improvements in Apparatus for the Fabrication of Concrete-Construction Elements, of which the following is a specification.

This invention relates to apparatus for making concrete building elements, and it comprises an improved construction according to which a single, specially-constructed mold and a coacting plunger or ram are utilized to simultaneously form a plurality of blocks or the like.

The mold is preferably arranged within a frame or casing embodying rigidly-related side, front and bottom walls, and a rear wall which is pivotally or hingedly related to the bottom wall so as to rock or swing about its lower edge. The front wall of this frame has its lower portion cut away for the greater part of its length to form a horizontal opening, and the mold proper is adapted to slide bodily, drawer-fashion, through this opening into and out of the frame; improved means being provided whereby the movable rear wall of the frame and the mold may be locked against outward movement when the mold occupies its operative position within the frame. The means in question may advantageously comprise rods which connect the front and rear walls of the frame and which have springs associated with them, the springs having a tendency to shift the rods and the movable wall in a rearward direction. The forward ends of the rods project loosely through the front wall and are equipped with cam devices which are adapted to ride over a member on the front wall of the mold, thereby forcing the rods to move forwardly, carrying the movable wall with them. The rear end of the mold abuts against the movable rear wall, and the engagement of the cams with the front wall of the mold serves to retain the parts in fixed position.

The invention resides in the improvements above stated, and it also resides in the provision of filling pieces which are supported at their upper ends upon the upper edges of the side walls of the frame and which bear upon the upper edges of the side walls of the mold, the inner sides of the filling pieces forming continuations of those of the mold sides. These filling pieces are removed with

the molded elements by inverting the apparatus upon the ground or upon the floor of the work-room.

The invention further contemplates the provision of improved devices for guiding the drawer mold during its sliding movements into and out of frame; and for that purpose, the front wall of the frame is formed with a series of vertical slits which extend upward from the upper edge of the previously-mentioned opening and which correspond in number and location to the side walls and the partition walls of the mold, the said walls projecting upwardly into the slits. The partition walls, however, terminate some distance short of the top of the frame; and because of that fact they will not extend completely through the mass of concrete material to be molded, in consequence whereof the upper portion of the molded mass will not be severed completely through. To overcome that objection, the plunger or ram used with the apparatus is provided on its under face with depending cutting ribs which are arranged immediately above and in line with the partition walls, so that at the end of the compression stroke of the plunger, these cutting ribs and the partitions will meet, thereby insuring the complete separation of the several building elements from one another.

Other and further improvements and advantages are comprised in the invention and will become apparent as the description proceeds.

An embodiment of the invention is illustrated by way of example in the accompanying drawings, in which:

Figure 1 is a front elevation of the frame of the apparatus.

Fig. 2 is a plan view thereof.

Fig. 3 is a longitudinal vertical section of the mold proper taken on line 3-3, Fig. 5.

Fig. 4 is a front view of the mold.

Fig. 5 is a plan view thereof.

Fig. 6 is a vertical cross-section on line 6-6, Fig. 2, showing the mold within the frame, the movable rear wall of the frame being open.

Fig. 7 is a fragmentary end view of the frame, showing the movable wall closed.

Fig. 8 is a longitudinal vertical section on line 8-8 of Fig. 6.

Fig. 9 is a detail cross-section on line 9-9, Fig. 8.

Fig. 10 is a front view of the complete

apparatus, with the guide in place in the frame.

Fig. 11 is a longitudinal section of the guide taken on line 11—11, Fig. 12.

5 Fig. 12 is a plan view of the guide.

Fig. 13 is an end view of the guide.

Referring more particularly to the drawings, the apparatus therein illustrated comprises, as previously stated, two main elements, viz: a rectangular frame or casing, and a mold proper removably fitting in the frame and providing the mold cavities or compartments; and, in conjunction with said elements, a removable ram or plunger.

15 The frame or casing comprises side walls 13, fixed and movable front and rear walls 14 and 19, and a bottom or base plate 20; the parts 13, 14 and 20 being suitably connected together. The wall 14 has its lower portion cut away between its ends for the greater part of its length, as shown in Fig. 1, to form an open space immediately above the bottom plate or wall 20; and said wall 14 is provided at suitable intervals with 20 parallel vertical slits 15 which extend upward from the upper edge of such cut-away part or opening. The front and rear walls 14 and 19 are directly connected together by means of a pair of cross-rods 22 (Fig. 25 7) which are rigidly fastened at their rear ends to the end portions of wall 19 and project loosely at their front ends through the end portions of wall 14, their projecting portions carrying cam latches 25 for a purpose presently stated. These rods are normally thrust in a rearward direction by the action of springs 23 which bear at one end against the fixed front wall 14 and at the other end against collars 24 fastened on the rods; the 30 result being that the movable rear wall 19, which is hingedly or pivotally supported on the base 20 by means of springs 21 (Fig. 6), is caused to normally assume the outwardly-inclined position represented in Fig. 45 6. The latches 25 are employed to effect the forward movement of said rods and, consequently, the movement of wall 19 into closed position, as hereinafter described, when the mold proper is in place in the frame.

50 The aforesaid mold, as shown in Figs. 3, 4 and 5, comprises vertical side or end walls 17, a series of intermediate vertical walls or partitions 16 and a bottom wall 18, all bolted or otherwise fastened together. The 55 walls 17 and 16 correspond in number and position to the slits 15 in the fixed front wall 14 of the frame, and are disposed in exact alignment therewith so as to permit the mold to be moved bodily outward and inward of the frame in drawer-fashion; the lower edges of the said walls resting slidably upon the bottom frame wall 20 and terminating some distance below the mold bottom 18 (Figs. 3, 4 and 8). The mold cavities or 60 compartments formed by the spacing of

the partitions 16 from one another and from the walls 17 have open rear ends which are adapted to be closed by the movable rear frame wall 19; the latter being provided at its inner face with recesses or depression 70 31 to receive projections 30 on the rear ends of the partitions 16. The front ends of the compartments are closed by the front wall 66 of the mold, and to the outer face of this wall 66 there is secured a horizontal bar 26, the ends of which project beyond the ends of said wall for cooperation with the latches 25; the arrangement being such that when said latches are swung downwardly into engagement with the outer faces of the bar 80 ends, the cam-shaped inner faces of the latches, in riding across the bar ends will produce a forward movement of rods 22 and, hence, an inward movement of wall 19, so that the parts will thus be locked in closed or operative position. When the latches are swung back into their normal raised position, out of engagement with the bar, the springs 23, which were compressed by the 85 previous locking operation, will be free to expand, forcing rods 22 backward and opening wall 19. The mold can then be moved outward and the molded blocks or other building elements removed from its compartments.

To facilitate manipulation of the mold, it may be provided with suitable handles 27 which, in the construction illustrated, are fastened to bar 26; and to prevent complete withdrawal of the mold from the casing, co-acting stops 28 and 29 can be employed, the stops 28 being fastened to the under face of the mold bottom 18, adjacent the rear edge thereof, and the stops 29 being fastened upon the upper face of the frame bottom 20 at the 90 front thereof, (Figs. 5, 6 and 10).

In addition to the parts above described, a pair of removable side pieces or fillers 32 and a guide element 36, also removable, are provided. The side pieces 32, as shown in Fig. 8, are of angle section and comprise horizontal and vertical wings or flanges; the former being adapted to rest upon and be supported by the flanged tops of the side walls 13. The vertical wings are designed 100 to rest upon the upper edges of the walls 17 of the mold, and their inner faces form continuations of those of said walls 17, as will be seen. These parts 32 are disengaged 105 when the mold is drawn outwardly of the 110 frame.

The guide 36 is of rectangular, skeleton construction, and is adapted to rest upon the top of the frame. It is likewise of angle section, and its outwardly-extending supporting wings or flanges carry pins 37 115 (Figs. 8, 10 and 11) for removable engagement in alining holes or sockets 38 (Fig. 2) formed in the flanged tops of the frame walls 13 and in the horizontal supporting 120 130

wings or flanges of the filling pieces 32 (Fig. 8). Springs 39 (Figs. 10-13) may also be attached to the side flanges or wings of the guide to catch over the frame and thus assist in maintaining the guide in place.

The ram or plunger used to compress the material into the mold, comprises a block or body 33 of a size and shape to fit easily within the guide 36 (see Fig. 8), and is provided upon its under face with transverse cutting ribs or knives 34. It will be observed that the partitions 16 in the mold terminate some distance short of the top of the frame, so that under ordinary conditions the tendency would be to form a single molded article only partially separated or severed into its several component parts. By providing these ribs or knives, however, and arranging them exactly below and in line with the said partitions, the latter and the ribs or knives will ultimately contact during the descent of the plunger and the molded mass of material will be severed completely through. Depending wedge-shaped elements 35 may also be attached to the under face of the plunger centrally above the several compartments of the mold, to exert a distributing action upon the mass of material about to undergo compression.

While in the above description reference has been made to the use of partitions 16 in the mold to divide the latter into a plurality of compartments, it is to be understood that the partitions may be omitted if it is desired to mold a single large block or similar building element at a time, rather than several blocks of smaller size. In such event, the slits 15 in the fixed front wall 14 of the frame will likewise be omitted.

The operation of the invention is believed to be apparent from the foregoing and, hence, to require no separate or additional explanation.

45 I claim as my invention:—

1. Apparatus for making concrete building elements, comprising an open-topped frame embodying rigidly connected side, front and bottom walls, and a rear wall hingedly related to the bottom wall to swing about its lower edge, said front wall having a horizontal opening; and a mold embodying connected side, bottom and front walls and open at its rear, said mold movable bodily inwardly and outwardly of the frame through said opening, drawer-fashion, and adapted to abut at its open rear end against the rear wall of the frame when in closed position.

60 2. Apparatus for making concrete building elements, comprising an open-topped frame embodying connected side, front, rear and bottom walls, the front wall having a horizontal opening and vertical slits extending upwardly from the upper edge of said

opening; and a mold slideable bodily, drawer-fashion, inwardly and outwardly of the frame through said opening and embodying vertical side walls which project upwardly into said slits to be guided thereby.

3. Apparatus for making concrete building elements, comprising an open-topped frame embodying rigidly connected side, front and bottom walls, and a rear wall hingedly related to the bottom wall to swing about its lower edge, said front wall having a horizontal opening and vertical slits extending upwardly from the upper edge of said opening; and a mold slideable bodily, drawer-fashion, inwardly and outwardly of the frame through said opening and embodying vertical side walls which project upwardly into said slits to be guided thereby.

4. Apparatus as claimed in claim 3, in which the sliding drawer mold has a front wall but is open at its rear end, and is adapted to abut at said end against the rear frame wall when in closed position so that said frame wall will close the mold.

5. Apparatus for making concrete building elements, comprising an open-topped frame embodying connected side, front, rear and bottom walls, the front wall having a horizontal opening and a series of vertical slits extending upwardly from the upper edge of said opening; and a mold slideable bodily, drawer-fashion, inwardly and outwardly of the frame through said opening; said mold embodying vertical side walls and one or more vertical partition walls disposed between and in spaced, parallel relation to the mold side walls, said side and partition walls being arranged in line with and projecting upwardly into said slits to be guided thereby.

6. Apparatus for making concrete building elements, comprising an open-topped frame embodying stationary side, front and bottom walls, and a rear wall movably related thereto, the front wall being formed with a horizontal opening; connecting members between the front and rear walls having springs associated with them for normally rocking the rear wall outward of the frame; a mold slideable bodily, drawer-fashion, inwardly and outwardly of the frame through said opening; and means for locking said movable wall and the mold in closed position.

7. Apparatus for making concrete building elements, comprising an open-topped frame embodying stationary side, front and bottom walls, and a rear wall movably related thereto, the front wall being formed with a horizontal opening; connecting members between the front and rear walls having springs associated with them for normally rocking the rear wall outward of the frame;

a mold slidable bodily, drawer-fashion, inwardly and outwardly of the frame through said opening; and locking means carried by said connecting members for engagement 5 with the mold when the latter is in closed position, to hold said mold and said movable wall against outward movement.

8. Apparatus for making concrete building elements, comprising an open-topped frame embodying stationary side, front and bottom walls, and a rear wall movably related thereto, the front wall being formed with a horizontal opening; connecting members between the front and rear walls having springs associated with them for normally rocking the rear wall outward of the frame; a mold slidable bodily, drawer-fashion, inwardly and outwardly of the frame through said opening; and cams carried by 15 said connecting members for engagement with the mold when the latter is in closed position, to hold said mold and said movable wall against outward movement.

9. Apparatus for making concrete building elements, comprising an open-topped frame having a horizontal opening in its front wall; a mold slidable bodily, drawer-fashion, inwardly of the mold, through said

opening and including vertical side walls 30 which are spaced from the side walls of the frame; and removable filling pieces supported upon the upper edges of the side walls of the frame and bearing upon the upper edges of the side walls of the mold, the inner 35 faces of said filling pieces constituting continuations of those of the said frame sides.

10. Apparatus for making concrete building elements, comprising an open-topped frame; a removable mold therein embodying one or more vertical partitions dividing the interior of the mold into compartments and terminating short of the top of the frame; and a plunger for compressing the concrete in said compartments, movable into 40 the frame through the open top thereof and provided upon its under face with one or more cutting ribs disposed immediately above and in line with said partitions so as to contact with the latter at the end of the 45 inward movement of the plunger and thereby sever the molded material completely 50 through.

In testimony whereof I affix my signature.
EMILE VICTOR PREUSS.
